Thompson & Moore

Shoe-Sole Machine,

No 11,500.

Patented Aug. 8, 1851.

UNITED STATES PATENT OFFICE.

JOHN THOMPSON, OF MARBLEHEAD, AND A. S. MOORE, OF LYNN, MASSACHUSETTS.

MACHINE FOR CUTTING BOOT AND SHOE SOLES.

Specification of Letters Patent No. 11,500, dated August 8, 1854; Antedated February 8, 1854.

To all whom it may concern:

Be it known that we, JOHN THOMPSON, of Marblehead, in the county of Essex and Commonwealth of Massachusetts, and A. S. 5 MOORE, of Lynn, in the county and Commonwealth aforesaid, have invented certain new and useful Improvements in Machines for Cutting Out the Soles of Shoes and Boots; and we hereby declare the following to be a 10 full, clear, and exact description of the same, reference being had to the annexed drawings, making part of this specification, in which—

Figure 1 is an isometric view of the machine, Fig. 2 is an end view of the same, Fig. 3 a front view, Fig. 4 a section through the sliding boxes which give motion to the knives, Fig. 5 a front and end view of the stop plate, Fig. 6 a view of the hollow pinion and cylinder partly broken away to show the spiral spring within. Fig. 7 detached view of cutter head, Fig. 8 front view and plan of one of the knives with one of the clamps.

25 Similar letters indicate like parts in all the drawings.

To enable others skilled in the art to make and use our invention we will proceed to describe its nature and operation, giving first 30 a general description of the machine and then the particular improvements which we have added thereto.

A is the framework of the machine, B the table upon which the strips of leather are 35 fed to the knives, C, the trough which receives the soles as they are cut off by the vertically vibrating knives *a*, *a*, the operation of which will be hereafter described.

D is the main driving shaft carrying the 40 fly wheel E and running in boxes F upon the main frame of the machine.

G is a crank upon the shaft D which is connected by the pitman I with the treadle H, by working which a rotary motion is 45 communicated to the shaft D.

K is a frame or carriage which slides vertically in grooves in the frame work to which it is furthermore confined by the straps *c*, or in any other analogous manner.

50 A motion up and down is communicated to this frame by the following means.

d is a crank pin or wrist pin placed eccentrically upon the end of the shaft D. To this crank pin is connected the pitman I, 55 one end of which is attached to the sliding frame K. As the shaft D is made to revolve,

a vertical motion up and down is thus communicated to the frame K and the parts connected therewith which will now be described.

M is the cutter head secured to the shaft *e* which has its bearings in the vibrating frame K, and is seen in dotted lines in Fig. 3, where it passes through the cylinder *f* to be hereafter referred to. The knives *a*, *a* 60 are curved in such a manner that one of them shall form one side of a sole and the other the other side, the cutter head being forced to make a half revolution each time it descends, so that the knives are operated 70 alternately upon the leather.

O is an adjustable sliding gage rest which may be slid more or less through its carrying bar P the position of the rest being regulated by the scale upon its shaft which 75 is made fast to the bar P by the thumb screws *i*. To the bar P is communicated a vibratory motion upon its points of suspension *l*, each time the knives descend for the purpose of allowing the soles to fall as they 80 are cut in the following manner.

m are stationary arms projecting from the main frame of the machine which carry the gage bar P.

n is a coiled spring which tends constantly 85 to retain the gage in the position represented in Fig. 1, ready to receive the end of the leather strip and gage the sole to be cut.

p is an arm attached to the gage bar which passes beneath the cylindrical extremity *q* of the cutter stock. As now the latter descends the arm P is vibrated and the forward end of the gage is caused to descend, as seen in dotted lines in Fig. 2, out 90 of the way of the sole which is thus permitted to fall.

r is a finger upon the arm *p* which, striking against the carrying arm *m* limits the return motion of the bar P and gage O as they are brought up by the spring *n*.

100 Q is an adjustable guide rest the position of which is regulated by the graduated scale *k* according to the length of the sole to be cut, and which is secured in position by the confining screw *l*.

We will now describe the improvements which we have made in the above machine and the parts more immediately connected therewith.

110 Our first improvement consists in a peculiar method of rotating the cutter head, which may be described as follows: *f* is a hollow

cylinder seen detached in Fig. 6, and having a pinion t upon its inner end. This cylinder fits over one end of the shaft e of the cutter head as seen in Figs. 1 and 3. a is a flat spiral spring one end of which is secured to the interior of the cylinder f and embracing the shaft e . If now when the cylinder is in place upon the shaft e , it be turned in one direction the spring binds upon the shaft and the latter is thereby rotated. When however the cylinder is turned in the opposite direction the spring relaxes its hold upon the shaft which then remains at rest. A vibrating rotary motion is communicated to the cylinder f in the following manner. R is a toothed sector having an arm w which receives a vibratory motion from the treadle H through the connections T , V , etc., as seen in Fig. 1. A rotary vibratory motion is thus communicated to the pinion t which gears with the sector R , and the shaft e and cutter head receive an intermittent rotary motion, and in order that these may be arrested at the precise instant when the knife is in a position to make a cut, the following device is resorted to. w is a disk secured to the shaft e having a flange y upon its inner surface in which are cut two slots z , z . a' , Fig. 3, is a flat steel spring secured to the sliding frame K at b' and moving up and down therewith. c' is a tooth or latch attached to the spring a' in such a position that as the disk w revolves with the shaft e and cutter head, the tooth c' falls into one or the other of the slots or notches z , and thus the shaft is held stationary until such time as the tooth c' is withdrawn from the notch z , which is accomplished in the following manner. d'' is a stationary cam piece attached to the main frame of the machine immediately beneath the spring a' and in such a position that as the frame K descends the lower end of the spring is forced in and the tooth is thus withdrawn from the slot z . This is effected at the last instant of the descent of the knives which are thus left free to revolve, the tooth c' resting upon the flange y until as the disk revolves it again falls into the other slot z . The operation of this part of the mechanism is as follows: As the treadle descends, the cylinder f slips freely upon the shaft e which remains locked by the tooth c' upon the spring a' . As the treadle ascends, the coiled spring u binds upon the shaft e and the latter is turned half a revolution, or until the tooth c' again falls into the notch z .

In the machines heretofore in use for the purpose of cutting boot soles, the power by which the knives were rotated was applied to them simultaneously with that by which they were elevated, and the consequence was that the knives commenced turning before they were released from the gutter which is very soon worn beneath them into the bed of

the machine, and thus considerable unnecessary strain and friction was produced. To remedy this evil we have adopted the following device which constitutes our second improvement.

By reference to Fig. 2 it will be seen that the crank G (which carries the pitman I of the treadle H) and the crank pin d are relatively so placed upon the shaft D that the pin d arrives at the lowest point of its circuit, while the crank G is still descending, and consequently the frame which carries the cutters commences to ascend before the knives begin to turn, the rotary motion of the latter being derived directly from the treadle through the connections T , V , etc. The knives are thus entirely free from the bench beneath before they begin to rotate and all unnecessary strain and friction are avoided.

Our third improvement has for its object the insuring of the ascent of the knives and treadle whether the machine be worked fast or slow, or in whatever part of the operation the machine be stopped, so that they may at all times be in a position to be operated and so that the crank G shall never be left upon its center or at the lowest point of its circuit, or indeed in any other position in which it cannot be instantaneously started by pressure upon the treadle. E is a fly wheel upon the shaft D which if sufficiently heavy would be perfectly competent to raise the treadle and carrying frame K so long as the machinery was in rapid motion, but where it is constantly stopped and started and never worked at a high velocity, it is evident that the weight of the carrying frame and treadle would depress the crank into its lowest position whenever the machine was stopped and it could not then be started by the treadle alone. To obviate this inconvenience I have so loaded the fly wheel with the weight A' that the combined weight of the treadle and frame K shall be overbalanced, so that the machine shall always be left in the position indicated in Figs. 1, 2, and 3, ready to be again started by pressure upon the treadle.

Our fourth improvement consists in a method of hanging the knives in the cutter head, so that they may be instantaneously adjusted without loosening the screws by which they are confined, for the purpose of narrowing or widening the toes and heels as required by the different sizes of the soles. The knives a are confined between curved clamps d' e' which clamps are secured to the cutter head in the following manner, f' are mortises through the cutter head in which slide boxes g' the motion of which is governed by the screw h' . A pin, seen in dotted lines in Fig. 4 passes through a groove in the end of the screw to confine it to the box g' . Through holes x' in these

boxes (Figs. 4 and 7) pass the screws i' which confine the cutter clamps together. It is evident therefore that as the boxes g' are moved by the screws h' , the knives will 5 also move with them. And in order that the toes and heels of the cutters may move in correspondence with each other, the knives with their clamps are pivoted to the cutter head in their center, the pin k' , projecting from the cutter head, entering a suitable hole in the clamp. From the above 10 it is evident that the knives may be adjusted for differing widths of toe and heel without loosening the screws which confine them to 15 the cutter head.

What we claim as our invention and desire to secure by Letters Patent is—

1. The combination of the sector and pinion with the cylinder and clamp spring, operating substantially in the manner described and for the purpose set forth.
2. We do not claim the mere adjustment of the crank G , and eccentrics on the shaft D . But what we do claim is—communicating both a vertical and an intermittent rotary motion to the knives, from the con-

tinuous motion of the fly wheel by the means above set forth, (to wit, the eccentrics operating the vertical slides which support the cutter shaft; and the geared cylinder, or its equivalent, engaging and disengaging with said shaft, and operated by the sector m or its equivalent, the motion of which is derived from the crank G as shown and described) or by other means substantially equivalent thereto, whereby we are enabled to secure the partial ascent of the knives, before the commencement of their revolution, by the proper adjustment of the eccentrics to the crank G . 40

3. Passing the screws which confine the knives to the cutter head through the sliding boxes g' , in the manner described for the purpose of adjusting the knives to different widths of toe and heel without loosening 45 the screws which confine them to the cutter head.

JOHN THOMPSON.
A. S. MOORE.
